FILTER PAPER HOLDER

James V. Smithson, St. Louis, Mo.

Application February 14, 1949, Serial No. 76,267

3 Claims. (Cl. 210—160)

1

This invention relates to strainers, generally, and concerns itself more particularly with a filter paper holder.

It is an object of the invention to provide a filter paper holder which automatically forms a filter cup from a flat filter paper when the latter is clamped in the holder.

Another object of the invention is to provide a device of the type described which may be folded into a flat, compact object for convenient storage in a minimum space.

A still further object of the invention is to provide a filter paper holder from which a used filter, together with its contents, may be quickly and easily removed for disposal without soiling the hands.

Other objects and advantages of the invention will become apparent as the specification proceeds and a more comprehensive understanding of the invention will be afforded from the following detailed specification when considered in conjunction with the accompanying drawing, in which

Fig. 1 is a top view of a filter paper holder embodying the instant invention,

Fig. 2 is a side view thereof showing the same with its parts positioned for storage, and

Fig. 3 is a side view of the holder showing the same with parts thereof positioned to receive a filter paper.

Briefly stated, the invention contemplates a holder comprising two concentric rings, one of which is mounted for pivotal movement into the other to clamp the marginal section of a flat filter paper between the rings, the outer ring being provided with a handle for convenient holding. The inner ring carries a bow which is pivoted therein for movement into the plane of the inner ring and into a plane normal thereto. When in the latter position the bow forms the filter paper into a filter cup as the inner ring is pressed into the outer ring to clamp the filter paper as aforesaid.

More specifically, the holder comprises, in one embodiment of the invention, an outer ring 11 formed from a single piece of metal strip to provide a vessel engaging supporting extension 12 and a handle extension 13, the latter having a suitably shaped handle 14 fitted thereon. A second, or inner, ring 15 is mounted for movement into the outer ring about a pivot taking the form of a pin 16 by means of which the ring 15 is connected to the handle extension 13 of the ring 11.

The inner ring 15 supports a wire bow 17, the

2

ends 18 and 19 of which are bent and passed into holes in the ring so that the bow may be moved into its supporting ring as shown in Figs. 1 and 2 or to the position it occupies in Fig. 3. This ring also has fixed thereto a lug 21 which serves as a stop for preventing the inner ring from passing through the outer ring and also acts as a finger tab by means of which the inner ring is raised outwardly from the outer ring.

To condition the holder for use as a strainer the inner ring 15 is raised above the outer ring 11 and the bow 17 is pivoted out of its supporting ring all as is shown in Fig. 3. A flat filter paper (not shown) is then placed on top of the outer ring 11 and the ring 15 is pressed downwardly until the lug 21 rests on the ring 11. The initial movement of the ring 15 carries the bow 17 into contact with the filter paper and presses it downwardly to form a filter cup, the marginal section of the paper being clamped between the two rings to hold the same in place in the holder.

After use, the inner ring is raised by means of the lug 21, providing for the disposal of the used filter paper in an obvious manner without touching it with the hands.

When not in use, the bow 17 is moved into the ring 15 and the latter into the ring 11 as viewed in Fig. 2. With its parts in this position, the holder, though providing a strainer of the well known cup shape, can be stored in a compartment of reduced height, such as a drawer of a kitchen table.

Various changes may be made in the details of construction, within the scope of the appended claims, without departing from the spirit of this invention. Parts of the invention may be used without the whole and improvements may be added while retaining some or all of the advantages of the invention.

What is claimed is:

1. A filter paper holder comprising a first ring member, a second ring member adapted for movement into the said first ring member to clamp a filter paper between said members, and a cupping bow member pivotally mounted at its ends in said second ring member adapted to form said filter paper into a filter cup as said second member is moved into said first member.
2. A filter paper holder comprising an outer ring member having as a part thereof a handle extension, an inner ring member mounted for movement into and out of said outer member about a pivot connecting the inner member to the outer member within said handle extension,

and a rigid cupping bow pivotally connected at its ends to said inner member for movement into, and normal to, the plane of said inner ring member.

3. A filter paper holder comprising first and second ring members, said second ring member being adapted for movement into the first to clamp a filter paper between said members, a rigid cupping bow pivotally connected at its ends to said second ring member for movement into, 10 and normal to, the plane of said second ring member, and a lug connected to said second ring member providing a stop for limiting the movement of this member into the first ring member, and means for withdrawing the second 15 member from the first member.

JAMES V. SMITHSON.
